UNITED STATES PATENT OFFICE.

HARRY A. KOENIG, OF PHILADELPHIA, PENNSYLVANIA.

GAS AND AIR PRESSING-IRON.

No. 884,169.

Specification of Letters Patent.

Patented April 7, 1908.

Application filed January 2, 1906. Serial No. 294,139.

To all whom it may concern:

Be it known that I, HARRY A. KOENIG, a citizen of the United States, residing at Philadelphia and State of Pennsylvania, have invented a new and useful Improvement in Gas and Air Pressing-Irons, of which the following is a specification.

My invention relates to certain new and useful improvements in gas heated pressing irons and has for its object to provide a flame distributor in connection with the iron so that the flame will be evenly distributed on the iron.

Another object of my invention is to provide a device which is very simple and cheap in construction and one which can be attached to irons of this kind now in use.

Another object of my invention is to provide a device that will overcome the difficulties now existing in irons of this character, of the flame passing to the rear of the iron leaving the front part of the iron without heat.

A further object of my invention is to provide an improved burner in connection with the iron which can be quickly and easily removed, and cleaned when desired.

With these objects in view, the invention consists of the novel features of construction, combination and arrangement of parts, hereinafter fully described and pointed out in the claims.

In the drawings forming a part of this specification: Figure 1 is a longitudinal sectional view of the iron. Fig. 2 is a plan view 35 of the flame distributor. Fig. 3 is a perspective view of the same.

Referring to the drawings A, indicates a hollow casting forming the body of the iron which is provided with the usual handle B, 40 and an opening formed in the rear of the iron having a hinged door A². A burner C, is secured to the top of the iron adjacent the front of the same, by a screw C', and projects down into the chamber through an opening 45 formed therein. The burner is provided with a vertical passage C², having an inwardly projecting beveled wall C³, so as to lessen the size of the passage and give the air and gas a uniform mixture.

50 A horizontal passage C⁴, connects with the passage C², at its end and is provided with a

perforated plate C⁵, forming the burner proper. The upper end of the passage C², is connected to a tube D, through which the air and gas is fed to the burner. 55

Arranged in the chamber of the iron, adjacent the burner is a casing E, inverted V-shaped in cross-section, forming a flame distributor and is secured therein by a screw E'. The casing is provided with a central partition E², having a beveled forward side provided with a groove E³, which communicates with the notch E⁴, formed in the bottom of the partition and it will be readily seen that the flame from the burner will strike the partition and be forced forward to the front part of the iron. The opening E⁴, will allow enough of the flame to pass through to the rear of the iron to heat the same. 60

The casing tapers downwardly from the partition and is provided with a notched end E⁵, through which the burner is adapted to be ignited. Notches E⁶, are formed in the sides of the casting adjacent the end E⁵, through which the heat is adapted to escape. 65

Having thus fully described my invention, what I claim as new and desire to secure by Letters Patent is:—

1. In an iron of the kind described, the combination with a chamber provided with a burner at one end, a flame distributor arranged in said chamber adjacent said burner, said distributor being inverted V-shaped in cross section and provided with a transverse partition having a beveled grooved side communicating with a notch in the partition, the beveled side of the partition being adjacent the burner, for the purpose described. 80

2. In an iron of the kind described, the combination with a chamber provided with an opening, of a burner arranged in said chamber projecting out through said opening, and a casing inverted V-shape in cross-section arranged adjacent the burner in the chamber, a transverse partition formed in said casing provided with a beveled grooved side, for the purpose described. 90
